UNITED STATES PATENT OFFICE

ELMER A. SPERRY, OF BROOKLYN, NEW YORK, ASSIGNOR TO SPERRY DEVELOPMENT COMPANY, OF DOVER GREEN, DELAWARE, A CORPORATION OF DELAWARE

FUEL INJECTING AND IGNITING MEANS FOR OIL ENGINES

Application filed May 25, 1922. Serial No. 563,735.

This invention relates to internal combustion engines using oil as a fuel, and in which the oil is injected into the cylinder by means of super-compressed air to effect vaporization. It has been found in large engines that when the inlet valve is throttled down for idling, the pressure under which the fuel is injected into the cylinder is often cut down to an extent sufficient to prevent effective spraying and vaporization. This invention has for one of its objects the provision of means whereby the amount of fuel supplied to the cylinder may be cut down at will, without materially affecting the character of the oil spray produced or the pressure under which the diminished charge of fuel is injected into the cylinder. For this purpose, there are provided a plurality of inlet valves in place of the single valve heretofore used, so that instead of throttling the valve to reduce the quantity of fuel supplied to the cylinder, as was formerly the case, one or more of the inlet valves in the present invention may be rendered ineffective while the remaining inlet valves each operate at full efficiency. In this manner proper vaporization is obtained even when the fuel supply is cut down.

A further object of this invention is the provision of means automatically controlled by the speed of the engine for cutting in or out one or more of the inlet valves.

Another object is the provision of a novel, highly efficient and inexpensive packing for plungers, valve stems and similar operating members.

Other objects and advantages will herein-after appear.

Referring to the drawings wherein I have shown what I now consider to be the preferred forms of my invention,

Fig. 1 is a plan view of a cylinder provided with a plurality of inlet valves and showing one form of valve-actuating mechanism.

Fig. 2 is a vertical section through a cylinder head equipped with valves which are sim-

ilar to those shown in Fig. 1, and illustrating a second form of valve-actuating mechanism.

Fig. 3 is a plan view of a cylinder head equipped with a plurality of inlet valves, and showing means whereby one or more of said valves may be rendered effective.

Fig. 4 is a vertical section through one form of inlet valve and valve-operating mechanism.

Fig. 5 is a plan view showing manual and automatic control means for controlling the means which renders the valves effective.

Fig. 6 is a plurality of separated sections showing the relative positions of the valve stems and the means which renders the valves effective.

Fig. 7 is a front elevation, partly sectioned, of the valve-operating means and controlling means therefor.

Fig. 8 is a view similar to Fig. 4, but showing another form of valve-operating mechanism.

Fig. 9 is a vertical section showing my novel packing applied to the plunger of a pump.

Fig. 10 is a section taken on the line X—X of Fig. 4.

In Fig. 1 there is shown diagrammatically at 10 a cylinder head which in this instance is equipped with four inlet valves shown at 11, 12, 13, 14 which may be of the type shown in Fig. 4. Although four valves are shown here, it should be understood that the invention applies where the cylinder head is provided with more or less valves. Each of these valves comprises an inlet 15, through which the fuel is admitted under pressure to the chamber 16, one or more passages 20 extending from chamber 16 to the nozzle or orifices 19 (see Fig. 10), and a valve-stem 17 normally seated at 18 to close said nozzle or orifices. For opening the valve there may be provided an operating lever 25 (see Fig. 4) journaled on a fixed shaft 26 and provided with arms 27 which engage the upper end of the valve stem 28.

at 28, so that upon raising lever 25 the valve-stem is raised to lift the valve off its seat, and the fuel is discharged through nozzle 19 under its full pressure.

- 5 As illustrated, the cylinder is provided with four valves and the operating levers 25 of said valves converge toward a point, so that all of said arms may conveniently be operated simultaneously. For this purpose 10 there is provided an operating member 30 pivoted at one end at 31 and having its other end 32 in contact with one arm 33 of a lever pivoted at 34 and whose other arm 36 is actuated by a timing cam 35 (see Fig. 1) carried upon a shaft 38. Each time the cam 15 engages the arm 36 it will depress the latter to raise arm 33, and hence, raise operating member 30 and the operating levers 25 in contact therewith. The contact between the 20 operating member 30 and operating lever 25 is effected by means of an adjusting screw 40 in the inner end of each of said levers 25. It will be obvious that by raising the screw above operating member 30, a distance 25 in excess of the rise of said member due to cam 35, the respective valve will not be operated. In this manner one or more of the inlet valves may be rendered temporarily ineffective and thus reduce the quantity of 30 fuel introduced into the cylinder at each charge. The fuel passing through the effective valves, however, is discharged under full pressure. This would not be the case where but a single valve was employed and throttled 35 to reduce the quantity of fuel injected into the cylinder at each charge, for in the latter case the pressure of injection would be correspondingly reduced and thus seriously impair the efficient vaporization of the fuel.
- 40 In Fig. 2 the same principle is embodied in a modified structure. A plurality of valves 41 having valve-stems 42 which, when depressed, open the respective valves to permit fuel to pass out of chambers 43, are adapted 45 to be operated by levers 45, similar to levers 25, and pivoted at 46. Contact between levers 45 and the valve-stems is effected by adjustable screws 50, similar to screws 40, and engaging flanges 44 on the upper ends of the 50 valve-stems. Levers 45 converge to a point, the inner ends contacting with a flange 47 at the upper end of a plunger 48 operating in a bore 49 in the head 52. For operating the flange 47 downwardly against the levers 45 55 there may be provided an operating member 55 similar to member 30 and adapted to be depressed by the cam 35 at regular intervals. In this modification one or more of the screws 50 may be withdrawn a distance greater than 60 the total downward movement of levers 45, so that the respective valves will not be operated. In this case also it is thus possible to reduce the quantity of fuel employed at each charge without reducing the pressure 65 of injection.

A third embodiment of my invention is illustrated in Figs. 3 and 5 to 7, inclusive. In this case also a plurality of valves are employed, each valve being preferably of the type shown in Fig. 8. These valves are similar to those shown in Fig. 4 with the exception of the operating levers 25, which have rods 55' attached thereto and projecting upwardly above the valves, said rods terminating in heads 56 whereby the valves are operated. 70 All of said heads 56 extend through openings 57, 58, 59, 60 in a plate 61, said plate having projections 62, 63, 64, 65, on its upper face, which extend substantially to the lower surfaces of the heads 56. Normally the projections are out of vertical alignment with the heads 56 and the plate 61 may be reciprocated, by cam 35 operating levers 70 and 71, without operating the valves. By rotating the plate 61 about a vertical central 75 axis, the projections may be brought into register with heads 56 to operate the valves upon reciprocation of the plate. It will be apparent from Figs. 3, 5 and 6 that the projections are so positioned that upon rotation of 80 plate 61, these projections will engage successively beneath the heads 56. Thus in Fig. 5, projection 62 will be the first to engage a head 56 to render one valve effective. Upon further rotation of plate 61, projection 63 will 85 engage a head 56, while the head on projection 62 rides further therealong. Still further rotation of plate 61 will render a third and a fourth valve effective successively. It 90 will be understood that as many projections are provided as there are valves, in this case, four. When all the valves are effective, i. e., in position on their respective projections so as to be operated by reciprocation of the 95 plate, they will appear as shown in plan in Fig. 3. If it is desired to reduce the quantity of fuel supplied to the cylinder at each charge, the plate 61 may be rotated in the direction of the arrow in Fig. 3 until one or 100 more heads, as desired, leave the projections. Each of the valves which remain effective supplies its full charge under full pressure to the cylinder, and so does not diminish the vaporizing effect of the injection. 105 For rotating the plate 61, the latter may have a hub 75 to which is fixed a crank 76, said crank being rotated by any suitable linkage. In the present instance, this linkage includes a link 77 connected at one end to crank 76 and at the other end to one arm 78 of a bell-crank 79, the other arm 80 of said bell-crank when raised or lowered operating 110 to rotate crank 76 and plate 61. The arm 80 may be set by a handle 81 forming one arm of a bell-crank 82, the other arm 83 of which has a pin and groove connection 84 with a tube 85. The end of arm 80 has a similar pin and groove connection 86 with 115 said tube, so that by operating handle 81, 120

tube 85 may be raised or lowered to rotate bell-crank 79 and plate 61.

The amount of fuel supplied to the cylinder may thus be initially set by the handle 81, and by connecting tube 85 to the movable elements 87 of a governor, so that movement of said elements causes movement of tube 85, and hence of plate 61, the speed may be controlled by said governor. Assume that handle 81 is set originally so that one valve is effective and that the governor is set for a certain speed. The movable elements of the governor will open as many valves as are necessary to attain the desired speed. If the governor is later set for a slower speed, it will automatically cut out certain of the valves.

In all of the modifications hereinbefore described, it is possible to adjust the throw of the valve-stem. In the modifications of Figs. 1 and 2 this is accomplished by adjusting the screws 40 and 50 respectively, of the effective valves, or by the screw in the end 32 of arm 30 in Fig. 1, or by varying the position of the lever arm 36 relative to cam 35 on shaft 38. By suitably limiting the movement of arm 36, and by adjusting screws 40 or 50, or by providing other adjustable lost-motion connections between lever 30 and the valve stems, it is possible to open any number of the valves, as desired. In the modification of Figs. 3 and 5 to 7, inclusive, the adjustment is accomplished by raising lever 70 by means of a crank 90 and eccentric 91 to raise or lower the ends of lever 70 both with respect to the cam 35 and the end of lever 71, or by varying the effective length of the arms of lever 70 by moving the fulcrum of said lever to the right or left by an adjusting rod 92, or by adjusting a screw 94 in the end of lever 71 to vary the degree of rotation due to operation of lever 70.

By referring to Figs. 4 and 8, it will be observed that the valve-stem 17 operates in a bore extending through a sleeve 100, said bore being cylindrical while the exterior of the sleeve is tapered downwardly and fits in a correspondingly tapered bore in the valve-head. A collar 101 surrounds the valve-stem 50 and is seated upon the upper end of the sleeve 100. The collar is threaded into the valve head to force the sleeve downwardly into the tapered bore and thus grip the valve-stem snugly to form an efficient casing. As the interior of the sleeve becomes worn in use, it is only necessary to screw collar 101 downwardly to force the sleeve further into the tapered bore and thus press the inner surface of the sleeve snugly around the valve-stem. The sleeve is preferably of copper and the valve-stem is fitted therein by lapping.

This novel lining may be applied wherever it is desired to pack any operating member such as a reciprocating or rotating rod, for example, in pumps. In Fig. 9 the sleeve is

shown applied to a plunger 105 in a pump cylinder 106, said plunger being carried by a cross-head 107 pivoted on a strap 108 eccentrically mounted on a shaft 109 to produce reciprocatory movement. The sleeve 100 surrounds the plunger and is tapered on its outer surface to fit into a correspondingly tapered bore in the pump cylinder 106. As the inner surface of the sleeve becomes worn, it is pressed further into the tapered bore by the collar 101 threaded into the cylinder 106. In this manner the sleeve may always be pressed snugly around the plunger 105.

It will be observed that the sleeve or lining is in effect a tubular wedge surrounding the member and interposed between the operating member and the casing. By adjusting the position of the sleeve in the tapered bore by means of collar 101, any desired pressure may be applied to the surfaces of the operating member to obtain any desired snugness of engagement between the sleeve and the member.

In accordance with the provisions of the patent statutes, I have herein described the principle of operation of my invention, together with the apparatus, which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having herein described my invention what I claim and desire to secure by Letters Patent is:

1. In an internal combustion engine, a cylinder, a plurality of fuel inlet valves therefor, means for opening said valves, and adjustable means whereby the number of valves opened by said first-named means may be varied.

2. In an internal combustion engine, a cylinder, a plurality of fuel inlet valves therefor, means for opening said valves, common means for actuating said first-named means, and adjustable means whereby the number of valves opened by the operation of said second-named means may be varied.

3. In an internal combustion engine, a cylinder, fuel inlet means therefor, said inlet means having means permitting the reduction of the quantity of fuel admitted comprising a plurality of separately operable inlet valves, and means whereby the number of said valves which are rendered effective may be varied.

4. In an internal combustion engine, a cylinder, a plurality of fuel inlet valves therefor, means for opening said valves, and means whereby one or more of said valves may be

positioned beyond the range of said first-named means so as to be unaffected thereby.

5. In an internal combustion engine, a cylinder, a plurality of fuel inlet valves therefor, means for opening said valves, and means whereby said valves may be positioned relative to said first-named means so that certain of said valves may be operated thereby and certain other of said valves may be positioned beyond the range thereof so as to be unaffected thereby.

6. In an internal combustion engine, a cylinder, a plurality of fuel inlet valves therefor, means for opening said valves, a connecting means between each of said valves and said first-named means, and means whereby any of said connecting means may be rendered ineffective so that the corresponding valves will not be opened by said first-named means.

20 7. In an internal combustion engine, a cylinder, a plurality of fuel inlet valves therefor, means for opening said valves, a member having a plurality of connecting means adapted to engage the valves, one of said connecting means for each valve, said member being movable to bring said connecting means into effective position so that operation of said first-named means will open one or more of said valves, said connecting means being so positioned on said member that movement of said member in one direction will bring said connecting means successively into effective position and movement in the opposite direction will bring said connecting means successively into ineffective position.

8. In an internal combustion engine, a cylinder, a plurality of fuel inlet valves therefor, means for opening said valves, a member rotatably mounted and having a plurality of connecting means adapted to engage the valves, one of said connecting means for each valve, said member being rotatable to bring said connecting means into effective position so that operation of said first-named means will open one or more of said valves, said connecting means being so positioned on said member that rotation of said member in one direction will bring said connecting means successively into effective position and rotation in the opposite direction will bring said connecting means successively into ineffective position.

55 9. In an internal combustion engine, a cylinder, a plurality of fuel inlet valves therefor, means for opening said valves, a member having a plurality of connecting means adapted to engage the valves, one of said connecting means for each valve, said member being movable to bring said connecting means into effective position so that operation of said first-named means will open one or more of said valves, said connecting means being so positioned on said member that movement of said member in one direction will bring said connecting means successively into ef-

fective position and movement in the opposite direction will bring said connecting means successively into ineffective position and means for moving said member.

10. In an internal combustion engine, a cylinder, a plurality of fuel inlet valves therefor, means for opening said valves, a member having a plurality of connecting means adapted to engage the valves, one of said connecting means for each valve, said member being movable to bring said connecting means into effective position so that operation of said first-named means will open one or more of said valves, said connecting means being so positioned on said member that movement of said member in one direction will bring said connecting means successively into effective position and movement in the opposite direction will bring said connecting means successively into ineffective position, means for moving said member, and means whereby said last named means may be controlled by the governor of the engine.

11. In an internal combustion engine, a cylinder, a plurality of fuel inlet valves therefor, means for opening said valves, said valves having valve-stems, a head on each of said stems, a plate mounted beneath said heads and spaced therefrom, said plate having a plurality of projections, one for each head, said plate being movable to bring said projections into engagement with said heads, so that operation of said means will open said valves.

12. In an internal combustion engine, a cylinder, a plurality of fuel inlet valves therefor, means for opening said valves, said valves having valve-stems, a head on each of said stems, a plate mounted beneath said heads and spaced therefrom, said plate having a plurality of projections, one for each head, said plate being movable to bring said projections successively into engagement with said heads so that operation of said means will open said valves.

13. In an internal combustion engine, a cylinder, a plurality of fuel inlet valves therefor, means for opening said valves, said valves having valve-stems, a head on each of said stems, a plate mounted beneath said heads and spaced therefrom, said plate having a plurality of projections, one for each head, said plate being movable to bring said projections into engagement with said heads so that operation of said means will open said valves, said projections being positioned on said plate so that certain of said projections may be brought into engagement with their respective heads to render the respective valves effective while others of said projections are out of engagement with their respective heads to render the respective valves ineffective.

14. In an internal combustion engine, a cylinder, a plurality of fuel inlet valves

therefor, means for opening said valves, said valves having valve-stems, a head on each of said stems, a plate mounted beneath said heads and spaced therefrom, said plate having a plurality of projections, one for each head, said plate being movable to bring said projections into engagement with said heads, so that operation of said means will open said valves, said projections being so positioned on said plate that movement of said plate in one direction will bring said projections successively into effective position and movement in the opposite direction will bring said projections successively into ineffective position.

15. In an internal combustion engine, a cylinder, a plurality of fuel inlet valves therefor, means for opening said valves, said valves having valve-stems, a head on each 20 of said stems, a plate rotatably mounted beneath said heads and spaced therefrom, said plate having a plurality of projections, one for each head, said plate being movable to bring said projections into engagement with 25 said heads so that operation of said means will open said valves said projections being so positioned on said plate that rotation of said plate in one direction will bring said projections successively into effective position and rotation in the opposite direction 30 will bring said projections successively into ineffective position.

16. In an internal combustion engine, a cylinder, a plurality of fuel inlet valves therefor, means for opening said valves, a 35 member having a plurality of connecting means adapted to engage the valves, one of said connecting means for each valve, said member being movable to bring said connecting means into effective position so that operation of said first-named means will open one or more of said valves, said connecting means being so positioned on said member that movement of said member in one 40 direction will bring said connecting means successively into effective position and movement in the opposite direction will bring said connecting means successively into ineffective position, means for moving said member, hand controlled means for operating said last named means, and means whereby said member-moving means may be controlled by the governor of the engine.

50 17. In an internal combustion engine, the combination with the cylinder, of a plurality of fuel valves therein, means for opening and closing said valves and means for varying the extent of movement of said first-named means, the valves being arranged so 55 that when the first named means is adjusted for limited movement, certain of said valves remain closed.

18. In an internal combustion engine, the combination with the cylinder, of a plurality 60 of fuel valves therein, means for opening

and closing said valves and means for varying the extent of movement of said first-named means, a lost motion connection between each of said valves and said first-named means, said connections being adjustable so that when the first named means is adjusted for limited movement, certain of said valves remain closed.

In testimony whereof I have affixed my signature.

ELMER A. SPERRY. ⁷⁵
